UNITED STATES PATENT OFFICE.

WILLIAM YATES JACK, OF NEW YORK, N. Y.

WELL-CASING SPEAR.

1,155,926.

Specification of Letters Patent.

Patented Oct. 5, 1915.

Application filed May 16, 1914. Serial No. 839,075.

To all whom it may concern:

Be it known that I, WILLIAM Y. JACK, a citizen of the United States and a resident of the city of New York, borough of the Bronx, 5 in the county of Bronx and State of New York, have invented a new and Improved Well-Casing Spear, of which the following is a full, clear, and exact description.

This invention relates to spears designed 10 for the purpose of removing lost well casings, the spear being of that type consisting of a plurality of dogs which are automatically retracted during the lowering of the tool into the well pipe and which automatically expand and grip the pipe as the tool is 15 raised, whereby the greater resistance of the casing's removal the greater is the grip of the dogs on the casing, so that slipping is positively prevented.

20 The invention has for its general objects to improve and simplify the construction of tools of the character referred to so as to be reliable and efficient in use, comparatively simple and inexpensive to manufacture, and 25 so designed that the fishing for and removal of a well pipe casing is greatly facilitated.

A further object of the invention is the provision of a spear which comprises a head having longitudinally slidable dogs thereon 30 which are confined in dovetailed grooves that collectively converge upwardly so that relative longitudinal movement of the head and dogs in one direction will contract the dogs inwardly so that they can enter a well 35 pipe or be withdrawn, while relative longitudinal movement in the opposite direction will expand or throw out the dogs so as to grip the well pipe or casing.

Another object of the invention is the provision of automatic locking means for locking 40 the dogs in indrawn position so that the spear can be released from and raised out of the well casing.

With such objects in view, and others 45 which will appear as the description proceeds, the invention comprises various novel features of construction and arrangement of parts which will be set forth with particularity in the following description and 50 claims appended hereto.

In the accompanying drawings, which 55 illustrate certain embodiments of the invention and wherein similar characters of reference indicate corresponding parts in all the views, Figure 1 is a side view of the well casing spear showing the same gripping a

well casing; Fig. 2 is a longitudinal section showing the tool just about to enter a well casing; Fig. 3 is a side view of the tool; showing the dogs in the act of releasing the 60 pipe; Fig. 4 is an enlarged sectional view on the line 4—4, Fig. 2; Fig. 5 is an enlarged sectional view on the line 5—5, Fig. 2; Fig. 6 is a sectional view showing the dog-carrying ring locked in dog retracted or re- 65 leased position for permitting the tool to be removed from the well casing; and Fig. 7 is a side view of a modified form of the tool.

Referring to the drawing, 1 designates the stem or shank of the tool which has on 70 its lower end a longitudinally extending head 2 formed with a centering point 3 at its lower end whereby the tool can be more readily entered into a lost well casing. This head is provided in its surface with longitudinally extending grooves 4 of dove-tailed cross-section, as shown in Fig. 4, and in each groove is a longitudinally slidable dog 5 which is of dove-tailed cross-section so that it will slide in its respective slot but will be 80 prevented from lateral displacement therefrom. The dove-tailed slots 4 collectively converge upwardly so that by an upward movement of the head with respect to the dogs the latter will be expanded, whereas 85 a reverse movement will cause a retraction or indrawing of the dogs, which actions are necessary respectively for gripping or releasing the well casing.

A shoulder 6 is provided at the upper 90 end of the head 2 where it joins the shank 1, and adapted to engage this shoulder is a ring 7 freely slideable on the shank 1, and on this ring are suspended the dogs 5, which have their upper ends entered in a chamber 8 in the ring and pivotally connected with the latter by studs 9 on the dogs entering apertures 10 in the wall of the chamber 8, although, of course, any other suitable means may be employed for connecting the 95 dog to the ring in such a manner as to provide for inward and outward lateral movement of the dogs. As shown in Fig. 2, each dog has three portions 11, 12 and 13 contacting with the bottom of its respective 100 groove 4, and as shown in Fig. 4, the bottom 14 of each groove is cut on an arc while the portions of contact of the dog are flat, so that a very small area of contact is provided between each dog and the head of the 105 tool. The lower ends of the dogs are beveled at 15 so as to freely enter the well cas- 110

ing, and at a point intermediate its ends each dog has a gripping surface 16 which may be serrated if desired to increase the bite on the well casing.

5 The foregoing description applies to both forms of the tool and the operation now to be explained will also apply to both of them. The tool is suspended and let down into the well by any suitable rigging, and 10 during the downward travel of the tool the dogs will be expanded as shown in Fig. 2, because the ring 7 will be resting on the shoulder 6. The point 3 first enters the well casing C, Fig. 2, and thereby guides the 15 tool into the casing until the dogs are arrested by the gripping surfaces 16 impinging on the upper edge of the casing, whereby the dogs are arrested in their downward movement while the head 2 continues to move downwardly until a point is reached where the dogs are retracted inwardly far enough to drop into the well casing. An upward pull is now exerted on the tool, which results in the head thereof moving 20 upwardly while the dogs are forced outwardly to cause their surfaces 16 to grip the well pipe, as clearly shown in Fig. 1, and after the tool is thus gripped to the well pipe, power is applied to draw up the tool 25 and well pipe with it.

It may be desirable in some instances to automatically release the dogs from the well casing while the latter is still in the well. For this purpose the dog-suspending ring 35 7 is provided with a plurality of spring-pressed bolts 17 which are disposed radially and have their inner ends normally engaging the stem 1 of the tool, and in this stem is a shoulder 18 formed by an annular groove 19 at a point considerably above the upper end of the head, and consequently by 40 moving the stem downwardly with respect to the ring 7 a point is finally reached where the dogs will spring into the groove 19 and thereby lock the ring 7 in a position where 45 the dogs are completely indrawn or retracted. The relative movement of the head and dogs to lock the latter in retracted position is greater than the normal range of movement necessary to enable the dogs to enter 50 the well pipe and to be thrown into gripping engagement therewith, and to prevent the ring 7 under ordinary conditions from reaching a point where the bolts snap into 55 the annular recess 19, a helical spring 20 is placed around the stem 1 with the lower end of the spring terminating somewhat below the shoulder 18, the upper end of the spring being engaged or connected with a 60 nut 21 screwed on the threaded portion 22 of the stem. By forcing the head and stem of the tool downwardly, as by means of a heavy blow while the dogs are engaged with a well casing, the spring 20 will be compressed by its contact with the ring 7, and

the stem thereby moves more than is ordinarily the case, so that as a consequence the groove 19 will come opposite the spring-pressed bolt 17, the result being that the bolts snap into the groove 19 and thereby 70 lock the ring 7 in raised position, whereby the dogs will be held retracted. In Fig. 3 the stem 1 is supposed to be moved downwardly by reason of a blow being imparted thereto, but the groove 19 has not come opposite the locking bolts 17, but as soon as the downward movement is completed, the bolts engage the shoulder 18, as clearly shown in Fig. 6, whereby the dogs are locked raised with respect to the head 2, so that 80 the tool can be removed from the well casing as shown in Fig. 3, the latter being shown partly raised in this figure as compared with the position shown in Fig. 2. The dog-releasing blow is imparted by a 85 collar 23 which freely slides on a guide sleeve 24 disposed around the threaded portion 22 of the stem and above the nut 21, such collar being fastened to the lower end of a section of pipe 25 which forms part of 90 the line by which the tool is suspended in lowering or raising. On the upper end of the threaded portion 22 of the stem is provided one or more nuts 26 which engage the collar 23, whereby the tool is suspended. 95 As a blow is to be imparted to the tool stem so as to retract the dogs and lock them retracted, the suspension line is allowed to drop very quickly, and in so doing the collar 23 will strike the nut 21 and impart a 100 powerful blow thereto, whereby the tool stem and head will be forced downwardly while the dogs are engaged with the well pipe, and hence relatively stationary, except 105 that the dogs are retracted during this downward movement of the tool head, and finally a point is reached where the spring-pressed bolt 17 engages the shoulder 18, as shown in Fig. 6, when the tool can be raised out of the well casing. The locking bolts 110 are provided with handles 17^a which project through slots 7^a in the ring 7, whereby the bolts can be retracted against the tension of their springs 17^b, and the slots 7^a have offsets 7^b into which the handles can 115 be turned to lock the bolts in retracted position. When the bolts are all retracted the ring 7 slides downwardly to the shoulder 6 of the tool body and then the bolts are again released so as to engage the stem 1, as shown 120 in Fig. 2.

From the foregoing description taken in connection with the accompanying drawings the advantages of the construction and method of operation will be readily understood by those skilled in the art to which the invention appertains, and while I have described the device which I now consider to be the best embodiment thereof, I desire to have it understood that the device shown is 130

merely illustrative and that such changes may be made when desired as are within the scope of the appended claims.

Having thus described my invention, I claim as new and desire to secure by Letters Patent:

1. A well pipe spear comprising a head having in its surface a plurality of longitudinal dove-tailed grooves, dogs slidable in the grooves and fitting the latter, and a supporting element on which the dogs are movably mounted and which is freely slidable axially of the tool, each groove and dog therein having contacting surfaces of which 15 one is convex and the other flat to provide longitudinal line contacts between the dogs and the head.

2. A well spear comprising a stem, a head on the stem, a dog slidably mounted on the head, a ring slidable on the stem and having a chambered under side into which the upper ends of the dogs extend, the surrounding wall of the chamber having apertures, and outwardly extending pins on the upper ends 25 of the dogs engaging in the openings for connecting the dogs with the ring.

3. A well casing spear comprising a stem, a head thereon, casing gripping jaws on the head and slidably longitudinally thereof for movement laterally inwardly and outwardly, a ring slidable on the stem, said ring having its under side chambered to receive the upper ends of the dogs, means for loosely connecting the dogs with the wall 35 of the chamber of the ring, whereby the dogs and ring move together longitudinally of the head and stem, spring-pressed locking means on the ring, and means on the stem with which the locking means engages 40 when the ring is fully raised to support the dogs in retracted position.

4. A well casing spear comprising a stem, a head thereon, casing gripping jaws on the head and slidably longitudinally thereof for movement laterally inwardly and outwardly, a ring slidable on the stem and to which the dogs are connected, spring-pressed locking means on the ring, means on the stem with which the locking means 45 engages when the ring is fully raised to support the dogs in retracted position, and tool suspending means including a device for im-

parting a blow to the stem and head for moving the stem to a position where the locking means engages the said means on the stem.

5. A well casing spear comprising a stem, a head, pipe gripping dogs on the head and slidably longitudinally thereof to move the dogs inwardly and outwardly, a ring slid- 60 able on the stem and to which the dogs are movably connected, spring-pressed bolts on the ring, a shoulder on the stem with which the bolts engage when the dogs are fully retracted, a tool suspension and pull means including a collar free to slide downwardly on the stem, an abutment on the stem to which the collar imparts a blow, and a yielding device on the stem for preventing the said shoulder from reaching to the locking bolts 65 of the ring except when the stem is moved downwardly by a blow imparted by the said collar.

6. A well casing spear comprising a stem, a head, pipe gripping dogs on the head and 75 slidably longitudinally thereof to move the dogs inwardly and outwardly, a ring slid- able on the stem and to which the dogs are movably connected, spring-pressed bolts on the ring, a shoulder on the stem with which 80 the bolts engage when the dogs are fully retracted, a tool suspension and pull means including a collar, spaced nuts on the stem and between which the collar has sliding movement, whereby a blow can be imparted 85 to the lower nut for forcing the stem downwardly with respect to the dogs to retract the latter, and a spring encircling the stem at a point below the lower nut and extending below the shoulder for preventing the 90 ring from reaching a point where the bolts thereof will engage the shoulder of the stem, except when the blow imparted to the stem compresses the spring by the ring engaging therewith and allowing the bolts to inter- 95 lock with the shoulder of the stem.

In testimony whereof I have signed my name to this specification in the presence of two subscribing witnesses.

WILLIAM YATES JACK.
